FIG. 4.

FIG. 3.

UNITED STATES PATENT OFFICE

NICHOLAS W. ANTHONY, OF NEW YORK, N. Y.

BURNER.

1,184,808.

Specification of Letters Patent.

Patented May 30, 1916.

Application filed September 3, 1915. Serial No. 48,904.

To all whom it may concern:

Be it known that I, NICHOLAS W. ANTHONY, of the city, county, and State of New York, have invented certain new and useful Improvements in Burners, of which the following is a specification.

This invention relates to liquid hydrocarbon burners and more particularly to burners designed for use in connection with 10 boiler and metallurgical furnaces.

The objects of the invention are to provide a burner of the low air pressure type having large capacity and in which a multiplicity of fuel jets are employed and the 15 flow of air regulated at the nozzles by a device which is common to all of the nozzles.

A further object of the invention is to provide a burner of the low air pressure type having a high efficiency as well as large 20 heat generating capacity.

A further object of the invention is to provide a burner of simple construction which may be readily taken apart or put together in accordance with the necessities of 25 actual practice.

Other objects and the features of novelty will be apparent from the following description taken in connection with the accompanying drawings, in which:

30 Figure 1 is a longitudinal section through one form of burner embodying my invention. Fig. 2 is a section on line 2—2 of Fig. 1. Fig. 3 is a longitudinal section of another form of the invention. Fig. 4 is a 35 section on line 4—4 of Fig. 3, and Fig. 5 is a fragmentary section of a modification of one of the details. Fig. 6 is a longitudinal section of still another form of the invention.

40 Referring to Fig. 1, 10 indicates the casing which is provided with the air pipe connection 11 and a removable plug 12, the latter being at the rear of the casing and carrying the fuel conduit 13. Within the casing 45 10, the conduit 13 is enlarged as shown at 14 and has connected therewith a plurality of pipes or nozzles 15 which discharge the fuel to the exterior of the casing, through the plugs or nebulizers 16. The nebulizers 50 are secured in a ring 17, which connects the ends of the nozzles 15 and is spaced from the wall of the casing 10 to provide the annular air passage 18. The ring 17 also has a central opening 19 for the discharge of

air. An adjustable cap 20 has a screw 55 thread connection 21 with the casing 10 and by adjusting this cap the space between it and the ring 17 may be varied to regulate the flow of air along the exterior of the ring. The cap 20 deflects the air from the passage 60 18 substantially at right angles to the fuel spray from the nebulizers 16, so that an annular flame will be formed, the air supplied through the central opening 19 supporting combustion on the interior of the flame. In 65 this way it is possible to supply the air at low pressure and provide the requisite quantity to burn the fuel with the maximum efficiency.

In the form of the invention shown in 70 Figs. 3 and 4, the plug 22 at the rear of the casing 10 is formed with a tubular extension 23 on the interior of the casing and to this extension there is secured a nozzle member comprising a hollow ring 24 and the branch 75 pipes 25 which are adapted to convey the fuel from the interior of the extension 23 to the space 26 on the interior of the ring 24. The ring 24 carries a series of nebulizers 27, as many nebulizers being employed as the 80 size of the ring 24 permits. The ring 24 is spaced from the casing 10 to provide the annular air passage 28 and may be provided with openings 29 between the nebulizers for the purpose of permitting the passage of air 85 from the interior of the casing. The central opening 30 in the ring 24 provides for the supply of a large volume of air in front of the burner and in order to increase the efficiency of the burner an outwardly flaring 90 deflector 31, having a screw thread connection with its support 25' whereby it may be adjusted, is arranged in the opening 30, and directs the air substantially at right angles to the inner surface of the ring of spray 95 from the nebulizers 27. The adjustable cap 30' on the casing has an inturned flange 30" which directs the air from the passage 28 against the spray from the nebulizer 27 and substantially at right angles thereto. In 100 this form of the invention the nebulizers produce an annular spray of fuel against the outer and inner sides of which air is directed by the flange 30" and the deflector 31, respectively. The air on account of 105 striking the fuel spray at right angles is distributed throughout the spray and not only produces an annular flame but results

in every particle of fuel receiving the requisite supply of air for the maximum efficiency of combustion.

The modification shown in Fig. 5 has the outwardly flaring deflector 32 carried by the ring 24^a and preferably formed integral therewith by means of the ribs 33. This deflector performs exactly the same function as the deflector shown in Fig. 3.

10 In the modification shown in Fig. 6 the rear plug 34 is made hollow and the nozzles 35 receive fuel therefrom. The ring at the outer end of the other forms is omitted but a central deflector 36 having a screw 15 thread connection with the plug 34 whereby it may be adjusted is preferably provided. The omission of the annular ring avoids having a mass of metal at the discharge end where it retards the flow of air 20 and, becoming hot, heats up the fuel. The flow of air through the burner, shown in Fig. 6, cools the nozzles and by maintaining the supply, for the nozzles, in the head 34, the oil is kept farther away from the flame 25 and cannot become too hot.

It will be evident from the drawings and the foregoing description that numerous arrangements of the nebulizers and air passages may be provided without departing 30 from the spirit of the invention as defined in the claims and therefore I do not wish to limit the invention to the exact details of construction shown and described.

Having thus described my invention, what 35 I claim and desire to secure by Letters Patent is:

1. In a device of the class described, the combination of a casing, an air pipe connection thereon, a detachable head at the rear 40 of said casing, a fuel supply conduit carried by said head, a plurality of nozzles arranged in a circle in said casing and supplied from said fuel supply conduit and adapted to discharge at the front of the casing, and adjustable members at the front of said casing 45 on the interior and exterior of said circle of nozzles each adapted to control the flow of a portion of the air to all of said nozzles.

2. In a device of the class described, the 50 combination of a casing, an air pipe connection thereon, a plurality of nozzles in said casing adapted to discharge fuel exteriorly of the casing, a ring connecting said nozzles, an outwardly flaring deflector arranged in 55 the center of said ring, and an adjustable cap for regulating the flow between said ring and said casing.

3. In a device of the class described, the 60 combination of a casing, an air pipe connection thereon, a ring at the discharge end of said casing, a plurality of nozzles on said ring, a conduit extending through the wall of said casing and communicating with the nozzles and an adjustable member on the discharge end of said casing adapted to co- 65

operate with said ring to regulate the flow of air.

4. In a device of the class described, the combination of a casing, an air pipe connection thereon, a ring at the discharge end of 70 said casing, a plurality of fuel nozzles carried by said ring, a fuel supply conduit communicating with said nozzles and an outwardly flaring air deflector at the center of said ring.

5. In a device of the class described, the combination of a casing, an air supply connection thereon, a member arranged centrally in the discharge end of said casing and having a central opening for the passage of air, a plurality of nozzles arranged 80 on said member in a circle about said opening, means for supplying fuel to said nozzles, an air deflector arranged in said central opening and adapted to direct the air 85 against the spray from said nozzles, and a cap on said casing for directing the air that is discharged around said member against the spray from said nozzles.

6. In a device of the class described, the 90 combination of a casing, an air supply connection thereon, a member arranged centrally in the discharge end of said casing and having a central opening for the passage of air, a plurality of nozzles arranged 95 on said member in a circle about said opening, means for supplying fuel to said nozzles, an adjustable air deflector arranged in said central opening and adapted to direct the air against the spray from said nozzles, 100 and an adjustable cap for directing the air, that is discharged around said member, against the spray from said nozzles.

7. In a device of the class described, the combination of a casing, an air supply connection thereon, a member arranged centrally in the discharge end of said casing and having a central opening for the passage of air, a plurality of nozzles arranged 105 on said member in a circle about said opening and adapted to coöperate to form a ring of spray, and means on the interior and exterior of said circle of nozzles for directing the air against the inner and outer sides of the ring of spray.

8. In a device of the class described, the combination of a casing, a plurality of nozzles arranged in a circle in said casing and adapted to discharge fuel exteriorly of the casing, an air passage arranged exteriorly 110 of the said nozzles, a central air passage within said circle of nozzles, and adjustable means adapted to deflect air currents passing through the external and the central air passages toward the fuel discharged from 115 the said nozzles.

9. In a device of the class described, the combination of a casing, fuel nozzles arranged in a circle in said casing and adapted to discharge fuel exteriorly of the casing, 120

a central air passage within said circle of nozzles and means adapted to deflect air currents passing through said central air passage toward the fuel discharged from the 5 said nozzles.

10. In a device of the character described, the combination of a casing, fuel nozzles arranged in said casing and adapted to discharge therefrom, a central air passage between 10 said nozzles, and an adjustable deflector arranged in the center of said central air passage.

11. In a device of the class described, the combination of a casing, an air supply connection 15 thereon, a plurality of fuel nozzles arranged in a circle in said casing and adapted to discharge the fuel from the casing in the form of a ring of spray, means for supplying fuel to said nozzles, adjustable means

on said casing adapted to direct a current of 20 air into the outer side of said ring of spray, and means for directing an annular current of air into the inner side of said ring of spray.

12. In a device of the class described, the combination of a casing, an air supply connection thereon, a plurality of fuel nozzles arranged in a circle in said casing and adapted to discharge the fuel from the casing in the form of a ring of spray, means for supplying fuel to said nozzles, adjustable means on said casing adapted to direct a current of air into the outer side of said ring of spray, and adjustable means for directing a current of air into the inner side of said ring of spray.

In testimony whereof I affix my signature.
NICHOLAS W. ANTHONY.
